UNITED STATES PATENT OFFICE.

JOHN T. HOPE, OF KANSAS CITY, MISSOURI.

VACUUM CLEANING-TOOL.

1,033,016.

Specification of Letters Patent. Patented July 16, 1912.

Application filed March 29, 1909. Serial No. 486,482.

To all whom it may concern:

Be it known that I, JOHN T. HOPE, a citizen of the United States, residing at Kansas City, in the county of Jackson and State of Missouri, have invented certain new and useful Improvements in Vacuum Cleaning-Tools, of which the following is a specification.

This invention relates to vacuum cleaning tools of that type adapted to rest upon and be moved along the object to be cleaned, to receive the dust and dirt withdrawn therefrom by suctional action produced up through the tool, and my object is to produce a tool of the character outlined by which a carpet or other object can be efficiently and expeditiously cleaned and which embodies the desirable features of simplicity, strength, durability and cheapness of construction.

A further object is to produce a tool of this character by which all of the exposed surface of a carpet may be cleaned irrespective of the proximity of the mop-board 25 of the room or any object therein.

With these objects in view the invention consists in certain novel and peculiar features of construction and organization as hereinafter described and claimed; and in order that it may be fully understood reference is to be had to the accompanying drawing, in which:—

Figure 1, is a view partly in front elevation and partly in central vertical section of a vacuum cleaning tool embodying my invention. Fig. 2, is an enlarged section corresponding to the part of Fig. 1 in section but showing a modified construction. Fig. 3, is a vertical section on the line VI—VI of Fig. 2. Fig. 4, is an end view of the tool equipped with sliding shoes or runners.

In the said drawing, 1 indicates a shell of suitable length and of inverted U-shape in cross section, by preference. The lower side of the shell is open to constitute a receiving opening or mouth and the shell is also provided with a tubular stem 2, constituting an exit opening, to be connected with a hollow handle, not shown, which in turn is adapted to be connected to a flexible hose or pipe leading to apparatus for creating suctional action up through the tool, as common in vacuum cleaning apparatus; this hose and apparatus being omitted as forming no part 55 of the invention.

Extending from end to end of the shell

and protruding through the receiving opening thereof is a movable partition or shoe for frictional contact with the object to be cleaned, and to hold the shell clear of such object. This movable partition preferably consists of a strip 3 of felt, secured by screw-bolts 4 or otherwise between the downwardly-diverging flanges 5 of a bar 6 provided with upwardly-projecting ears 7 pivoted on screw-bolts 8 or equivalent devices, secured in the end-walls of the shell, the arrangement being such that the shoe rocks on the floor or surface being cleaned, forwardly or rearwardly accordingly as the shell is moved forward or rearward. The result of the forward rocking movement of the shoe and advance movement of the shell, is to cause the rear wall of the latter and the rear side of the shoe to engage and establish 75 an air-tight joint or connection preventing dust-laden air from passing up in the shell rearward of the shoe. It also spaces apart the front wall of the shell and the corresponding face of the shoe so that the dust-laden air shall be drawn upward into the shell in advance of the shoe, the latter resting upon the floor so as to prevent air from a point rearward of the shoe from being drawn up into the shell in advance of the shoe.

When the shell is moved rearward the shoe rocks in the same direction so that its front side shall engage the front wall of the shell with an air-tight relation and open up 90 communication through the shell between the rear wall of the same and the corresponding side of the shoe, to permit dust-laden air to be collected rearward of the shoe only, it being understood that this 95 rocking action of the shoe only occurs as the direction of movement of the shell is reversed, that is, as it starts on its forward or rearward movement, it being also understood that in the cleaning operation the tool 10 is alternately pushed forward and pulled rearward in an obvious manner.

In Figs. 2 and 3, the tool is shown as equipped at its ends with carrying-wheels or rollers 12, and the shoe, of the type shown in Fig. 3, and correspondingly numbered, has elongated openings or slots 13 in the ears 7 to receive the inner ends of screw-bolts 8 secured in the end-walls of the shell.

In the construction shown by Figs. 2 and 3 the rollers 12 carry all of the weight of the tool except that of the shoe, and thus en-

able the operator to move the tool back and forth with no perceptible exertion, the shoe playing vertically on its pivot bolts 8 each time the movement of the tool is reversed. 5 It will also be apparent that a vertically-movable shoe adjusts itself to the surface of the floor and thus compensates for wear. 10 It is believed that a recapitulation of the operation is unnecessary other than to draw attention to the fact that by restricting the entrance of the air to the shell between a wall of the same and the adjacent side of the shoe, the suction created is of substantially twice the power it would be if air was permitted to pass into the shell at both sides of the shoe simultaneously,—in other words, by providing the tool with a narrow inlet it has greater pick-up power and the dust-laden air travels with the greater velocity than if 15 permitted to enter the tool at both sides of the shoe or if the shell was not equipped with the partitioning shoe. 20

This tool can be used on a polished floor or other object to great advantage as there 25 is practically no danger of the felt shoe scratching or marring the finish of such floor or object, it being also noted that the felt, being compressible, will adapt itself to slight irregularities in the surface of the 30 object upon which it is operated.

If desired felt or equivalent runners or stationary shoes 14, (Fig. 4,) as distinguished from the rotatable shoes or rollers

12, may be employed in conjunction with the vertically movable shoe of Figs. 2 and 3, as 35 the difference in friction between stationary shoes or runners and movable shoes or rollers would be immaterial in the operation of a tool of this character.

From the above description it will be apparent that I have produced a vacuum cleaning-tool embodying the features of advantage enumerated as desirable and which is susceptible of modification in various particulars without departing from the spirit 40 and scope of the appended claim. 45

Having thus described the invention what I claim as new and desire to secure by Letters-Patent, is,

A vacuum cleaning tool, comprising a 50 shell of inverted U-form in cross section and open at one side to receive dust-laden air and provided with a tubular stem as an exit for such air, and a shoe extending longitudinally within said shell and adapted for alternate engagement with the front and rear walls thereof and for vertical movement, and projecting through said open side for engagement with the object to be cleaned. 55

In testimony whereof I affix my signature 60 in presence of two witnesses.

JOHN T. HOPE.
